US00D763140S

(12) **United States Design Patent**
Gariglio et al.

(10) **Patent No.:** US D763,140 S
(45) **Date of Patent:** ** Aug. 9, 2016

(54) **BILLET PUSH ROD**

(71) Applicant: **Inter-Power Corporation**, Almont, MI (US)

(72) Inventors: **Gary M. Gariglio**, Metamora, MI (US); **Edward P. Potoczak**, Rochester Hills, MI (US); **Brian C. Smith**, Almont, MI (US); **David J. Wagner**, Port Huron, MI (US); **James W. Nankervis**, Imlay City, MI (US); **Patrick H. McRee**, Lapeer, MI (US)

(73) Assignee: **INTER-POWER CORPORATION**, Almont, MI (US)

(**) Term: **14 Years**

(21) Appl. No.: **29/522,763**

(22) Filed: **Apr. 2, 2015**

Related U.S. Application Data

(63) Continuation-in-part of application No. 29/497,584, filed on Jul. 25, 2014.

(57) **CLAIM**

What is claimed is the ornamental design for a billet push rod, as shown and described.

DESCRIPTION

FIG. 1 is a front view of the rod;

FIG. 2 is a top view of the rod shown in FIG. 1;

FIG. 3 is a rear view of the rod shown in FIG. 1;

FIG. 4 is a bottom view of the rod shown in FIG. 1;

FIG. 5 is a left-end view of the rod shown in FIG. 1;

FIG. 6 is a right-end view of the rod shown in FIG. 1;

FIG. 7 is a right end top perspective view of the rod shown in FIG. 1;

FIG. 8 is a right end bottom perspective view of the rod shown in FIG. 1; and,

FIG. 9 is a left end top perspective view of the rod shown in FIG. 1.

The broken lines in the drawings depict unclaimed environmental subject matter.

1 Claim, 5 Drawing Sheets
